UNITED STATES PATENT OFFICE.

MORGAN BROOKS AND MILTON KENT AKERS, OF URBANA, ILLINOIS.

MEANS FOR OPERATING ALTERNATING-CURRENT MACHINES IN PARALLEL.

No. 876,686.

Specification of Letters Patent.

Patented Jan. 14, 1908.

Application filed January 18, 1907. Serial No. 352,923.

To all whom it may concern:

Be it known that we, MORGAN BROOKS and MILTON KENT AKERS, citizens of the United States of America, and residents of Urbana, in the county of Champaign and State of Illinois, have invented certain new and useful Improvements in Means for Operating Alternating-Current Machines in Parallel, of which the following is a specification.

10 Our invention relates to the operation of any kind and type of alternating current machines.

For the sake of simplicity of description, we will explain the invention as applied to 15 single phase alternating current generators.

The several objects of the invention are to obtain approximately and automatically any desired distribution of load currents among a plurality of coupled alternating current 20 machines, without the employment of centrifugal and other mechanisms; to provide for self synchronizing such machines both on coupling and during operation while coupled; to permit the transfer of surplus energy from 25 a machine of high excitation to a machine of low excitation automatically, thereby improving the power factor of the system, and correspondingly increasing the capacity for the load current; to diminish hunting and 30 racing; to eliminate difficulties from differences of wave form; to be able to include and exclude from the circuit one or more machines, and cause those in use to properly and automatically divide the load among 35 themselves; and to operate successfully machines at different distant stations in parallel with proper dividing of the load currents automatically.

Other minor results will appear from the 40 following explanations.

Without regard to the scopes of invention which are attended to in the claims, the organization comprising our invention consists primarily of alternating current machines, 45 and inductive means for compelling a division of load currents among the several machines automatically, and secondarily, of self-synchronizing coils in circuit with said machines.

50 Other details will appear hereinafter.

We will now describe specifically, exactly what the drawing shows, and how the elements exhibited therein operate.

The single figure of drawing is a diagram 55 of the electric circuits and apparatus.

1, 2, 3, 4, 5, are alternating current gen-

erators connected to the bus bars B and C in parallel circuits. They may be of different sizes as indicated, our invention being applicable to like or dissimilar alternating current machines.

D¹, D², D³, D⁴, are transformers, whose respective primary coils are P¹, P², P³, P⁴, the first of which is in series circuit with a group composed of the generators 1 and 2 and the others of which are in series circuit with the remaining generators 3, 4, and 5 singly.

The secondary coils S¹, S², S³, S⁴, of the above named transformers are of a given phase, and are in a normally closed series circuit with each other. 1^a, 2^a, 3^a, and 4^a, are switches for short-circuiting the said secondary coils individually.

We will now set forth the operation of the system as far as the use of the transformers is concerned. They are designed to carry, in their primary circuits, currents preferably in direct proportion to the full load current of each machine, or group of machines, as the case may be, and in their secondary circuits 80 a single current alike in all transformers. When proportional currents are naturally flowing through each machine, the transformers, D¹, D², D³, D⁴, are non-inductive, since in their primary coils, P¹, P², P³, P⁴, are 85 the proportional currents for which they are designed, and the secondary coils, S¹, S², S³, S⁴, being all designed for the same current, are not only connected in a corresponding direction, but are in a closed circuit. Under 90 these circumstances, practically no electro-motive force exists at the terminals of the said transformers. Any change of the current from a single machine, as for example the generator 3, without a corresponding 95 change in the other generators, is opposed by the reaction of the primary coil of its transformer, D². If, however, the current through this last named primary coil does change, it causes, through the connected secondaries of 100 the transformers, a corresponding change in the current from all the other generators, approximately restoring the proper proportion of load currents. Similarly, any change of excitation or of driving force, in one generator, thus affects all generators. The useful result is the securing of an average electro-motive force and an equalization of power. The transformers are therefore so connected as to be approximately non-inductive 110 so long as the desired division of load current exists, but automatically inductive.

when the proper division is disturbed, whereby a satisfactory approximation of balance of the load current is restored. The non-inductive connection for balanced circuits is intended to apply specifically to the fundamental frequency of the current in any apparatus controlled, but will also apply to higher harmonic frequencies, provided these higher harmonics are similar in the several machines. Different higher harmonics, and harmonics in different phase relation to the fundamental, producing that difference in wave form, which is often a source of trouble in operating, become opposed by the relatively high inductance of the transformers for such unbalanced harmonics, and are checked thereby.

D^{1a} is an auto-transformer, one portion of the coil of which is in series circuit with the generator 1, while the other portion is in series circuit with the generator 2. Said auto-transformer is for action between the two generators 1 and 2, while the transformer D^1 is for action between these two generators 1 and 2, on the one hand, considered as a group of generators, and the other generators individually, on the other hand.

By simply closing the short-circuiting switches 1^a , 2^a , 3^a and 4^a , the alternating current generators 3, 4, 5, and the group 1, 2, may be placed in the ordinary parallel circuit connection without securing any balance of the load. The primary coils P^1 , P^2 , P^3 , P^4 , are all thereby rendered completely non-inductive for any value of current whatever, and their circuits have merely the almost negligible resistance of the coils. The core loss of the transformers is also trivial, since there is then no appreciable terminal voltage, which is a measure of core losses.

By opening the circuit closers G^1 , G^2 , G^3 , G^4 and G^5 , the alternating current generators 3, 4, 5, and the group composed of the generators 1 and 2, may be cut out of circuit.

45 The transformers may be cut out of circuit by opening the circuit closers g .

We do not allege that there is obtained a mathematical accuracy of control of the current loads by our invention, but such is not necessary in practice. We secure a balancing of the currents conformable to the rigid requirements in large or small plants.

In the operation of our system as above described, the alternating current generators

are apt to fall out of step with one another, unless connected together rigidly. To maintain them in step while independently driven we provide reactance coils, E^1 , E^2 , E^3 , E^4 and E^5 , preferably without iron cores, and connected in series with the respective machines and the extra or synchronizing bus bar Q and line bus bar B. The reactance coils also serve to synchronize the generators during the process of coupling the same in parallel circuit. These coils should be so designed as never to allow excessive current to flow between the generators 1, 2, 3, 4 and 5, even at opposition of phase, and yet to permit enough current to synchronize a generator to be connected, and to maintain it in synchronism. An impedance for these coils E^1 , E^2 , E^3 , E^4 , and E^5 , which will allow about half the full load current to flow on applying the full generator voltage, has been found satisfactory.

In normal operation, the cross currents are confined to these self-synchronizing reactances, since the impedance of the balancing transformers is entirely too great to allow sufficient cross currents to flow for maintaining synchronism under ordinary conditions. The current required in these synchronizing coils may be determined by an ammeter. Under favorable conditions, the synchronizing currents in these coils may be reduced to a negligible quantity, insuring the highest efficiency. They should not be cut out of circuit after the machines are coupled, for they not only synchronize on coupling, but during operation after coupling.

What we claim and desire to secure by Letters Patent, is,—

The combination of a plurality of alternating current machines connected in parallel circuit, electric transformers, primary coils for said transformers included in series circuit with the respective machines, and the secondary coils of a given phase, for said transformers connected in a closed series circuit with one another, and self-synchronizing reactance coils in circuit with the respective machines.

MORGAN BROOKS.
MILTON KENT AKERS.
